UNITED STATES PATENT OFFICE.

CHARLES M. HEETER, OF BUTLER, PENNSYLVANIA.

FISHING-TOOL.

SPECIFICATION forming part of Letters Patent No. 769,140, dated August 30, 1904.

Application filed November 30, 1903. Serial No. 183,099. (No model.)

To all whom it may concern:

Be it known that I, CHARLES M. HEETER, of Butler, Butler county, Pennsylvania, have invented a new and useful Fishing-Tool, of which the following is a full, clear, and exact description, reference being had to the accompanying drawings, forming part of this specification, in which—

Figure 1 shows in elevation my fishing-tool when in use in removing a detached bit or tool from an oil-well. Fig. 2 is a similar view seen at right angles to Fig. 1. Fig. 3 is a separate view of the fishing-tool, and Fig. 4 is a detail view showing the fishing-tool engaged with a different portion of the detached bit from that illustrated in Figs. 1 and 2.

The difficulties which have heretofore attended the removal of detached tools or bits from oil-wells have been the occasion of great expense and loss to oil-well drillers and operators; and it is the purpose of my invention to provide means for this purpose which shall be reliable in its action and which will enable the removal of bits or tools from wells more certainly and quickly than has been possible heretofore.

My invention consists in a fishing-tool of new construction; and it also consists in a drilling-tool having a lateral recess affording a shoulder for engagement by my fishing-tool or by fishing-tools of other construction.

In the accompanying drawings, Fig. 1, 2 represents a bit or drilling-tool which has been broken off and lodged in an oil-well, having been crowded against and into the soft rock at the side of the well in a manner which prevents its engagement by fishing-tools of the kind ordinarily employed. 3 is the fishing-tool which I employ for removing such bit. This tool consists of a head portion or socket 4, by which it is connected to the stem or string of tools 5, extending to the top of the well. The lower portion or shank of the fishing-tool is reduced in thickness and extends downwardly from one side of the head portion, so that it may be inserted along the side of the bit or tool to be removed, and it is provided with a hook 6, the extremity of

which is preferably made of hardened steel, so as to insure its engagement with the tool 50 to be removed.

7 is a spring guide or arm which extends from the fishing-tool preferably below the hook 6 and when the fishing-tool enters between the bit 2 and the wall of the well is 55 adapted to bear against the wall of the well and to exert upon the fishing-tool a pressure tending to push it toward the bit.

In the use of my fishing-tool it is lowered into the well until it passes between the side 60 of the bit 2 and the wall of the well, and when it comes opposite to an upwardly-recessed portion B, which I form for that purpose on the bit or drilling-tool, it is forced inwardly by the spring 7, and when it is next drawn up 65 the hook 6 will engage the recess B and the bit 2 can be drawn with the fishing-tool to the top of the well.

I prefer to form on the bit 2 one of the recesses B or B' on each side of the bit 2, so that 70 the fishing-tool will engage with the bit at whatever quarter of the hole it may enter between the bit and the wall. The fishing-tool, however, may be used to remove tools or bits which are not provided with recesses B or B'. 75 In this case if the hook 6 be made of hardened steel the spring 7 will cause it to bite upon the bit sufficiently to move it somewhat in the well and to dislodge it from the sides sufficiently to enable a horn-socket, (which is a 80 common fishing-tool,) to be inserted into the well and engage with it, whereas without the preliminary dislodging of the bit it is often difficult and sometimes impossible to cause the horn-socket to engage it.

Within the scope of my invention as defined in the claims the apparatus may be modified in construction in various ways, since

What I claim is—

1. A fishing-tool for deep wells having a 90 hook adapted to be inserted into the space between one side of a lodged tool and the side of the well, and a spring guide or arm adapted to press the hook toward the lodged tool; substantially as described.

2. A fishing-tool for deep wells having a 95

head or socket, a shank extending downwardly at one side of the head or socket, a hook, and a spring guide or arm; substantially as described.

- 5 3. A fishing-tool for deep wells having a hook adapted to be inserted into the space between one side of a lodged tool and the side of the well, and a downwardly-extending spring guide or arm adapted to press the hook

toward the lodged tool; substantially as described.

In testimony whereof I have hereunto set my hand.

CHARLES M. HEETER.
